UNITED STATES PATENT OFFICE.

CHARLES COESTER, JR., AND JAMES L. MOORE; OF BRIDGEPORT, CONN.

IMPROVEMENT IN GARTERS.

Specification forming part of Letters Patent No. 106,328, dated August 16, 1870.

To all whom it may concern:

Be it known that we, CHARLES COESTER, Jr., and JAMES L. MOORE, both of Bridgeport, in the county of Fairfield and State of Connecticut, have invented a new and Improved Garter, of which the following is a full, clear, and exact description, reference being had to the accompanying drawings, forming part of this specification.

Our invention consists in a garter made of wire or a strip of metal coiled into a spring, which, in its cross-section, may be either circular, elliptical, or of a flattened form, and which has its ends united or connected.

In the accompanying drawings, which illustrate our invention, Figure 1 is a view of a garter the transverse section of which is circular, showing it clasped; and Fig. 2 is a view of the same, showing it unclasped and extended.

Similar letters of reference indicate corresponding parts in the figures.

This garter is made by coiling a wire of brass or other elastic metal after the form of a helical spring and bending one end to form an eye, *a*, and the other end to form a hook, *b*. After the hook and eye have been thus formed, the ends of the wire may be soldered, to secure them and strengthen the hook and eye. The garter thus made is shorter in its normal condition than the circumference of

the portion of the leg which it is to encircle, so that when it is applied to the stocking on the leg and its ends secured by the hook and eye it will be stretched to such a degree as to produce sufficient tension to firmly hold the stocking in place. In a garter thus constructed there is not the liability to lose its elasticity, which is so common with the elastic garters now in use.

Instead of the garter being constructed as shown in the drawings, it may have its transverse section of an elliptical or flattened form, and, instead of having its ends bent into a hook and eye, may have a fastening or fastenings of other constructions attached thereto. The ends, however, may be permanently united or connected, in which case it must be put on by slipping it over the foot to its proper place on the leg.

What we claim as our invention, and desire to secure by Letters Patent, is—

A garter composed of a single piece of wire coiled in the form of a spring, and one end formed into an eye and the other into a hook, substantially as herein described, as a new article of manufacture.

CHARLES COESTER, JR.
JAS. L. MOORE.
